METHOD AND APPARATUS FOR DRYING

Joseph G. Dinwiddie, Waynesboro, Va., assignor
to E. I. du Pont de Nemours & Company, Wil-
mington, Del., a corporation of Delaware

Application October 15, 1936, Serial No. 105,741.

3 Claims.

(CL. 34—4)

This invention relates to a method and apparatus for drying coarsely or finely divided materials, such as by means of a continuous rotary vacuum drum drier. More particularly, it relates to a method and apparatus for drying materials containing a relatively small proportion of liquid.

In a continuous rotary vacuum drum drier, an enclosed drum is continuously rotated and vacuum is applied to the interior side of a screen or pervious fabric support covering the outer drum periphery and carrying on its exterior side the material to be dried. The material to be dried is supplied to the screen or other support in a regulated manner, such as by a hopper or star wheel feed device generally positioned above the drum. The material is spread to a uniform layer of desirable thickness by means of a doctor knife. A heated gaseous drying medium such as air, supplied by fans situated on opposite sides of the drum drier, is drawn through the layer of the material to be dried by the aforementioned vacuum. After the drum has rotated approximately 180 degrees, the material is sufficiently dry to be discharged into a hopper for suitable disposal.

The continuous rotary vacuum drum drier is particularly effective in drying crystalline materials, such as sodium bicarbonate, trisodium phosphate, and ammonium sulfate, or granular materials, such as cellulose acetate, and many other materials in a wide diversity of industries. This type of drier, however, has the disadvantage of a low unit capacity per unit of heated air employed in drying, particularly when employed for the drying of materials containing a relatively small proportion of liquid. This disadvantage has been a prime factor in retarding the extensive adaptation by the industries of the rotary vacuum drum drier that otherwise well deserved the most favorable recognition.

It is therefore an object of this invention to increase the unit capacity of a drier such as a rotary vacuum drum drier per unit of heated air employed.

It is another object of the present invention to secure a continuous layer of material to be dried across the entire width of a support in a rotary vacuum drum drier.

Other objects will be evident in the description of the invention given hereinafter.

These objects are accomplished, generally, by avoiding excessive eddy currents of gaseous drying medium in the vicinity of the moist material to be dried. I have found that the presence of such eddy currents causes areas of the support

to be denuded of moist material, thus allowing drying medium to be drawn thru the denuded areas of the support without contacting the moist material and without therefore exerting any substantial drying effect.

In order to arrive at a better understanding of the invention, reference is had to the following description taken in connection with the accompanying drawing. It is to be understood that this description is illustrative and not limitative.

In the drawing, Fig. 1 is a cross-sectional side view of a rotary vacuum drum drier in accordance with this invention; Fig. 2 is a front view of the knife spreader or doctor knife 4 in combination with the screen covered vacuum drum 3.

Referring to the drawing, moist material, such as granular cellulose acetate, having a moisture content of 20-50%, is dropped through a hopper 7 into a rotating star wheel feed device 14 that regulates the amount of material admitted to a feed chamber 10 and on to a screen support 21 covering the periphery of a drum 3 supported on stationary shaft 23 and slowly rotating in the direction of the arrow, such as by means of drive flange 27 and belt drive 28. The rotation of the drum carries the deposited material 22 past a doctor knife 4, adjustable to yield across the entire width of the periphery of the drum a layer of material approaching a uniform thickness of 1" to 1½", to a drying chamber 11. During the rotation of the drum 3 through the arc A to B, a vacuum of 8" to 15" of water is applied on the interior of the drum. The material 22 is dried by passage of heated air drawn inward through the layer of material by the vacuum. The heated air is supplied through the ducts 5 and 6 by means of the fans 15 and 16. During the rotation of the drum through the arc B to C, a blast of air or the like is applied on the interior of the drum 3 in order to assist the discharge of the dried material through the hopper 8 into bags, storage bins, or other suitable collecting means. No pressure or vacuum is exerted on the interior of the drum 3 during its rotation through the arc C to A.

It will be understood, of course, that rotary vacuum drum drying is preferably a continuous procedure and that the operations of charging, drying, and discharging the material occur simultaneously. Among other ways, this may be accomplished as follows: The interior of the drum is divided into compartments 30, each compartment having a screen support 21 at one end and the other end 29 communicating by holes or other suitable passages 33 with the interior of a partly

hollow stationary shaft 23 similarly provided with holes or other suitable passages. The interior of the shaft 23 is divided into two closed compartments 31 and 32 communicating directly with compartments 30. Vacuum is continuously applied to compartment 31 by means of vacuum pipe 34, and pressure continuously applied to compartment 32 by means of pressure pipe 35. In this way it is seen that vacuum is applied to some compartments 30 and pressure to others, so that vacuum is exerted on the screen support situated in the arc A to B and pressure on the screen support situated in the arc B to C. As the drum rotates, some compartments 30 move out of registry 10 with compartment 31 and into registry with compartment 32, and are replaced by other compartments 30 so that the pressure and vacuum are maintained sectionalized. In order to prevent both vacuum and pressure being applied at the same time to any one of the compartments 30, compartments 31 and 32 are divided by a wall 36 having a thick exterior portion 37 having a length of arc equal to or greater than the greatest length of arc of end 29 of any compartment 30.

25 Prior to the present invention, the feed chamber 10 consisted of a sealed compartment separated from the drying chamber 11 by the solid, flexible baffle 9 held in contact with the screen support 21 of the drum 3, such as by means of a spring 18, by a solid doctor knife corresponding to knife 4 spaced approximately 1" to 1½" from the screen support 21 and by the mass of material 22 admitted through the star feed wheel 14. The application of vacuum to the screen support 21 30 through the vacuum compartment 31 built up, therefore, a considerable vacuum in the feed chamber 10. On the other hand, the heated air supplied by the fans 15 and 16 maintained the drying chamber 11 at substantially atmospheric 35 pressure. As a result, there existed between the chambers 10 and 11 a substantial differential pressure that engendered a more or less violent influx of air through the space between the doctor knife 4 and the screen support 21. This influx of air 40 caused areas of the screen support to be denuded of material (hereinafter referred to as "channeling") which in turn diminished the efficiency of the drying process.

In the preferred form of the present invention, the difficulty of channeling is overcome by 45 substituting for the solid doctor knife hitherto employed a doctor knife 4 having perforations 41 of a suitable size and number to maintain the pressure in the chambers 10 and 11 substantially 50 equal, or at least sufficiently equal so that no disturbing air currents are drawn through the space between the doctor knife and the screen support 21.

It will be recognized, of course, by those skilled 55 in the art of drying materials that the preferred embodiment is susceptible to considerable modification without departure from the fundamentals of the invention. Thus, the holes allowing ingress of heated air into the chamber 10 need not necessarily be placed on the doctor knife but may instead be located at any suitable position in the chamber 10. Alternatively, the baffle 9 may be 60 perforated with holes of suitable size and shape and inclined at such an angle to the rotary drum 65 surface that the holes do not readily become clogged with material and that heated air from the duct 6 readily passes into the chamber 10. While in general the elimination of any differential pressure between the chambers 10 and 11 70 probably represents the optimum operating con-

dition, still in certain cases it may be advisable or even desirable to maintain a difference of pressure between chambers 10 and 11 of 2" of water, or even up to 3". In no case, however, should the difference of pressure be sufficient to induce air currents of enough magnitude to create channeling of the material on the screen support.

The invention is most applicable to materials which, as supplied to the rotary vacuum dryer, contain a relatively small proportion of liquid, such as less than 90% water, and usually less than 75% or 50% water. Such materials are peculiarly subject to channeling, while materials containing more than 90% liquid tend to mat down and cohere to a sufficient extent to avoid the disrupting influence of eddy currents of air. Among the materials which may be suitably dried by this invention may be mentioned granular and crystalline materials, such as flake and vacuum pan salt, sodium bicarbonate, trisodium phosphate, 20 and ammonium sulfate; metallurgical and quarry products such as building and phosphate sand; and light but free filtering materials such as ground regenerated cellulose film, cotton linters, and cotton seed meal.

25 The present invention has contributed considerably to the art of drying materials by increasing to a notable extent the efficiency and capacity of the rotary vacuum drum drier. Maintaining all other conditions such as temperature of the heated air, degree of vacuum, size of particles, size of the rotary drum, etc., the same, the use of this invention has increased the capacity of the rotary vacuum drier 50-75% or more. The increased capacity lowers the expense of drying and should promote more extensive adaptation of this type of equipment for a wide diversity of products throughout many industries. It is now possible to dry certain products by rotary vacuum drum drying that have never before been economically 30 dried by this process. As to products that have previously been dried advantageously on a rotary vacuum drum drier, the invention should result in a reduction of the cost of production that will render the products more readily available to the 35 public.

Any variation or modification of the invention as described, which conforms to the spirit of the invention, is intended to be included within the scope of the claims.

I claim:

1. An apparatus for drying material comprising a feed chamber, means for feeding to said chamber material to be dried, a movable support within said chamber, means for applying vacuum to the opposite side of said support, a regulating device for regulating the thickness of material to be dried on said support, said regulating device forming one boundary of said chamber, said support being adapted to move past said regulating device, a drying chamber on the opposite side of said regulating device from said feed chamber, means for supplying fluid drying medium to said drying chamber, and passages communicating between said drying chamber and said feed chamber for maintaining the pressure on opposite sides of said regulating device substantially equal.

2. An apparatus for drying material comprising a feed chamber, means for feeding to said chamber material to be dried, a movable support within said chamber, means for applying vacuum to the opposite side of said support, a doctor knife forming one boundary of said chamber, said support being adapted to move past said doctor

knife, a drying chamber on the opposite side of said doctor knife from said feed chamber, means for supplying heated air to said drying chamber, and openings in said doctor knife for the passage of air between said drying chamber and said feed chamber for maintaining the pressure on opposite sides of said regulating device substantially equal.

3. The process of suction drying of materials which comprises depositing the wet materials to be dried on the perforated surface of a drying element in a substantially enclosed depositing zone in which the side of the element opposite that on which the material is being deposited is maintained at a pressure substantially less than atmospheric, moving said drying element past a device for regulating the thickness of materials

thereon into a drying zone in which the side of the drying element containing the material is supplied with a gaseous drying medium having an elevated temperature and the opposite side of the element is maintained at a pressure substantially less than atmospheric, and passing gaseous drying medium to said depositing zone at a point spaced from the surface of the deposited material, and maintaining the pressure of gaseous drying medium in the depositing zone substantially equal to the pressure in the drying zone whereby to prevent movement of the gaseous drying medium from the drying zone to the depositing zone past the surface of the deposited material.

JOSEPH G. DINWIDDIE.
